Primary Examiner — Stacia Cadmus(74) *Attorney, Agent, or Firm* — Andrew F. Young, Esq.; Lackenbach Siegel, LLP(57) **CLAIM**

The ornamental design for a vehicle wheel rim, as shown and described.

DESCRIPTION

FIG. 1 is a right perspective view of a first embodiment of the invention.

FIG. 2 is a front elevation view of FIG. 1.

FIG. 3 is a left perspective view of FIG. 1.

FIG. 4 is a left side elevation view of FIG. 1, the right side, top plan, and bottom plan views being mirror images thereof due to the circular shape.

FIG. 5 is a partial perspective view of FIG. 1, as an illustrative aid, noting the details therein.

FIG. 6 is a right perspective view of a second embodiment of the invention.

FIG. 7 is a front elevation view of FIG. 6.

FIG. 8 is a left perspective view of FIG. 6.

FIG. 9 is a left side elevation view of FIG. 6, the right side, top plan, and bottom plan views being mirror images thereof due to the circular shape; and,

FIG. 10 is a partial perspective view of FIG. 6, as an illustrative aid, noting the details therein.

The broken line showing of the rear of the wheel, the valve stem hole, the bolt holes and center opening in the central hub area and portions of the rim spoke sides is included for the purpose of illustrating environment and forms no part of the claimed design.
